R. B. FISHER.
BUMMING POST.
APPLICATION FILED OCT. 11, 1919.

1,333,709.

Patented Mar. 16, 1920.

UNITED STATES PATENT OFFICE.

RAYMOND BENSON FISHER, OF HARVEY, ILLINOIS, ASSIGNOR TO BUDA COMPANY, A CORPORATION OF ILLINOIS.

BUMPING-POST.

1,333,709.

Specification of Letters Patent. Patented Mar. 16, 1920.

Application filed October 11, 1918. Serial No. 330,124.

To all whom it may concern:

Be it known that I, RAYMOND BENSON FISHER, a citizen of the United States, and residing at Harvey, in the county of Cook 5 and State of Illinois, have invented certain new and useful Improvements in Bumping-Posts, of which the following is a full, clear, and exact description, reference being had to the accompanying drawings, forming a part 10 of this specification.

My invention relates to bumping posts, and has reference, in an objective sense, more particularly to the provision of a novel spacing and holding means interposed and clamped between portions of the running rails and confronting end portions of the post rails which carry the bumping block, whereby the bumping post may be very readily and easily installed on the running rails 20 regardless of whatever size the latter may happen to be, and in a manner permitting the passage of vehicle wheel flanges between the confronting heads of said rail portions.

A further object of the invention is to 25 eliminate the customary practice of cutting away portions of the rail base flanges, which practice tended (1) to weaken the post structure particularly in the vicinity of rail joints, and (2) to reduce the seating capacity of these joints. By my invention the entire structure is simplified and cheapened, and its efficiency and utility is increased.

These, together with such other advantages as may hereinafter be described or are 35 incident to my invention, I attain by means of a construction illustrated in a preferred form in the accompanying drawings, wherein:

Figures 1 and 2 are views, respectively, in 40 top plan and in section of a bumping post to which my invention is shown applied, the lower right hand rail joint being sectioned horizontally to disclose the spacing block there employed;

Fig. 3 represents a sectional view of the block adapted for use with the largest size of running rail;

Fig. 4 is a vertical cross-sectional view 50 taken through the rail joint of Fig. 1, illustrating the practical application of the block of Fig. 3, when reduced on one side thereof, to fit a smaller size of running rail; and

Fig. 5 represents a view in perspective of the block of Fig. 4.

Referring to the drawings, the reference

character A denotes the running or main rails, and B the bumping block which is supported in the customary fixed relation by the post rails C. These latter diverge downwardly and outwardly from the block toward the running rails and terminate in substantially parallel end portions 6, each positioned to confront an opposed portion 7 of one of the running rails where the joint is to be made. The ensuing description relates 65 only to one of these joints as all of them are alike in every respect.

As will be seen from an inspection of Fig. 4, no portion of the foot or base of either rail is cut-away or reduced at the joint. Interposed between the rail portions 6 and 7 is an elongated spacing block 8 which is here positioned to seat on adjacent rail base flanges and whose inner and outer side faces respectively contact with the opposed faces of the webs 6' and 7' of said rail portions to space apart the heads 6^a and 7^a thereof, and thereby permit the passage therebetween of the wheel flange of a vehicle in its approach toward the bumping block B. These rail webs 80 are firmly clamped into a close and rigid association with the block by means of the clamping elements 9 which extend through medial openings 10 provided in the block for their reception to terminally engage the outer 85 faces of the webs. One of these elements may, if desired, take the form of a brace rod, as indicated by the reference numeral 9^a, connecting each pair of joints.

Above these openings 10, the spacing 90 block 8, which is preferably formed of metal (steel) or other workable material, is provided with a longitudinal depression in its upper face constituting a wheel flange groove 11, the portions 12 and 13 at the sides 95 thereof respectively being in contact with the underfaces of the rail heads 6^a and 7^a.

As will be obvious, the bumping post proper, together with the filler blocks and clamping elements are made, as a manufacturing proposition, for attachment to the fixed running rails without involving any change in the latter other than the drilling of the necessary holes for the clamping elements. These running rails are of course 100 variably sized, while the size of the post rails C is generally fixed, utilizing as for example a sixty pound rail for this purpose. In order to meet such a condition, the filler block, as initially manufactured has its outer 105 110

5 rail head engaging portion 13 enlarged in the vertical direction to accommodate the largest size of running rail likely to be met with, say for example a one-hundred and twenty pound rail. This enlargement is 10 designated at 14 in Fig. 3, and in the case of the application of the block to a running rail of the same size as that of the post rail, or approximately so as in Fig. 4, the enlargement is cut away or reduced to the requisite extent, roughly indicated by the dotted line 15 in Fig. 3. The structure is therefore admirably suited to meet varying situations, and in very simple and effective manner. It 20 will also be noted that a maximum degree of rail base support and rigidity of the joint is afforded, and that no portion of either rail base flange has to be cut away in order to permit the installation of the post. Other advantages will be apparent to those skilled in the art.

What I claim is:—

1. A spacing block for opposed variably sized rail sections having rail head supporting portions and a wheel flange groove formed therein between said portions, one of said portions being higher and narrower than the other said portion.
2. A filler means adapted for interposition as a connection between a supplementary rail section of predetermined size and a main rail section of undetermined size comprising an elongated block adapted to

35 seat upon adjacent base flanges of the sections and having its upper surface formed with a relatively narrow wheel-flange groove of substantial depth, said groove positioned nearer one side face of the block than the other side face to provide portions of varying height and width for engaging the heads 40 of said sections, the main rail head-engaging portion possessing relatively a greater height and a less width than the other said portion, substantially as and for the purpose 45 set forth.

3. A filler means adapted for use as a spacing connection between a post rail section of predetermined but less than the maximum main rail size and a main rail section whose size may be the maximum or less, 50 comprising an elongated block adapted to seat upon adjacent base flanges of the sections, and having its upper surface channeled to provide a relatively narrow wheel-flange groove of substantial depth which is 55 positioned to one side of the plane of the line of separation of the base flanges, thereby providing opposed rail section head-engaging portions of variable width, the main rail head-engaging portion being relatively 60 higher and of a lesser width than the other said portion whereby to present a surface conforming to the head of a main rail of maximum size and capable of being reduced to fit a main rail section of less size.

RAYMOND BENSON FISHER.
